UNITED STATES PATENT OFFICE.

MARY TURNER, OF NEW YORK, N. Y., ASSIGNOR TO THE BUTTERICK PUBLISHING COMPANY, (LIMITED,) OF SAME PLACE.

DESIGN FOR A LADY'S POLONAISE.

SPECIFICATION forming part of **Design No. 17,885**, dated November 15, 1887.

Application filed October 15, 1887. Serial No. 252,491. Term of patent 3½ years.

To all whom it may concern:

Be it known that I, MARY TURNER, of the city, county, and State of New York, have invented and produced a new and original Design for a Pattern of a Lady's Polonaise Costume; and I do hereby declare that the engraved prints accompanying this specification convey to any one accustomed to using paper patterns a clear understanding of how a garment made up by the pattern will appear.

The design shows a long polonaise and a round walking-skirt. The skirt exhibits a back drapery that falls in straight kilt-folds at the center to the lower edge. The polonaise displays close-fitting fronts that flare sharply a little below the waist-line, falling in long panels to the edge of the skirt and exhibiting

two draping plaits in the back edges near each hip. A close-fitting back that reveals the back drapery to the top between its back edges exhibits a coat-plait below the waist-line of each side back seam, falls even with the lower edge of the skirt, and flares from the fronts below the draping plaits in the latter, coat-sleeves, and a standing collar.

What I claim as my invention, and desire to secure by Letters Patent, is—

The design for a lady's polonaise costume, as shown in the engraved prints accompanying this specification.

MARY TURNER.
